UNITED STATES PATENT OFFICE.

JOHN MORRISON, JR., OF GLENS FALLS, NEW YORK.

BRUSH AND METHOD OF MAKING THE SAME.

1,280,810.

Specification of Letters Patent.

Patented Oct. 8, 1918.

Application filed July 14, 1917. Serial No. 180,630.

To all whom it may concern:

Be it known that I, JOHN MORRISON, Jr., a citizen of the United States, residing at Glens Falls, in the county of Warren and 5 State of New York, have invented certain new and useful Improvements in Brushes and Methods of Making the Same, of which the following is a full, clear, and exact description.

10 My invention relates to brushes and admits of general use, but is of special use in connection with brushes known in commerce as solid-back brushes—that is, flat brushes in which the back is made of wood 15 or the like, and has the form of a thin block, the bristles being arranged in tufts which project from a large, flat surface of the block.

More particularly stated, my invention relates to the manner in which the tufts of 20 bristles are secured to the brush-back.

Reference is made to the accompanying drawing forming a part of this specification, and in which like letters indicate like 25 parts throughout all of the views.

Figure 1 is a perspective of a brush, showing the same as partly broken away.

Fig. 2 is a plan view of the bristle plate, used in guiding the bristles and arranging 30 them into tufts.

Fig. 3 is a fragmentary section through a brush back, not yet ready to receive the bristles.

Fig. 4 is a fragmentary section, showing 35 the brush back appearing in Fig. 3, ready for use with the bristle plate appearing in Fig. 2.

Fig. 5 is a fragmentary section, showing 40 the brush back and bristle plate as used together, the bristles being now arranged into tufts.

Fig. 6 is a fragmentary section through the brush showing the same as nearly completed.

45 Fig. 7 is a section on the line 7—7 of Fig. 1, looking in the direction indicated by the arrows.

Fig. 8 is a fragmentary section showing the brush as made without the use of cement.

In practice I take a brush back 8, made 50 preferably but not necessarily of a single block of wood, and by boring or drilling I provide it with a considerable number of holes 9, arranged in parallel rows, and suitably positioned to receive the bristle tufts. 55 These holes are in the face or large front surface of the block.

I next drill or bore laterally into the block a number of smaller holes 9^a, each merging 60 into and diametrically crossing several of the holes 9, together forming a row. The holes 9^a are formed into a single row, extending nearly the full length of the block. Each hole 9^a, in this instance, extends not quite the full width of the block. Its point 65 of intersection, with each hole 9, is substantially midway between the top and bottom of such hole.

The holes are all best made by the use of gang drills or augers, but can be formed one 70 at a time or in any manner desired.

I next place the brush back in the position indicated in Fig. 3, and spread over its upper surface a small quantity of liquid cement or other adhesive, capable of drying, 75 hardening or setting.

The liquid cement sinks into the holes 9, filling each of them up to a greater or lesser extent from its bottom, as shown at 10 in Fig. 3. Owing to the viscosity of the cement, it forms in each hole a lining 11, varying in thickness. A coating 12 of the cement may adhere to the upper surface of the brush back, though this layer can be scraped or wiped off; and this is usually done. 80

I now take the bristle plate 13 and lay it flat down upon the brush back, as indicated in Fig. 4. The bristle plate is made of metal and provided with holes 14 extending through it, these holes being arranged in 85 rows and the rows being parallel with each other, as shown. The holes in the brush back correspond, as to number and arrangement, with the holes in the bristle plate.

If desired, the bristle plate may be 95 secured to the brush back before the latter is provided with holes, and the holes in the brush back may be made by drilling or bor-

ing through the holes in the bristle plate. By this arrangement the bristle plate serves as a guide for locating or positioning the holes in the brush back.

5 The holes 14 are each provided with a flaring portion 15, for the purpose of guiding the bristles into the holes.

10 The bristle plate is secured upon the brush back by screws 16 or other appropriate fastening members.

The bristles are shown at 17, and as here indicated are arranged into tufts which extend through the holes in the bristle plate, and into the holes in the brush back.

15 In this particular instance, I use single length bristles; that is, bristles having the same length as the tufts to be formed. Such bristles are much cheaper than double length bristles—or, in other words, bristles of sufficient length to be doubled or bent into U-form and thus formed into the tufts.

20 The single length bristles are showered upon the bristle plate in the usual or any desired manner, and they find their way into the holes. They are then pressed smooth or leveled so that the projecting ends are even, as indicated in Fig. 5.

25 The lower ends of the tufts are thus embedded in the cement masses with which the holes 9 are partially filled, as indicated at 18 in Fig. 5.

30 I next take a number of pins 19, made of tough, hard wood or metal, as desired, and drive these pins into the holes 9^a. Each pin 19 is thus driven through the respective base portions of a number of separate tufts forming a row, as may be understood from Figs. 1 and 6. Each pin 19, in this instance, extends nearly the full width of the block 8.

35 40 If desired, the exposed ends of the pins may be covered with a filling 20 of any appropriate material, such as putty, plaster of Paris, clay or the like. This is usually done for the purpose of improving the appearance of the brush, but it is not strictly essential.

45 As the pins 19 are driven through the tufts of bristles the holes it makes are not round. The pin has more or less tendency to split or cleave the tufts, as indicated more particularly in Fig. 6.

50 55 As each tuft of bristles is pierced by a pin acting somewhat after the manner of a wedge, the bristles on each side of the pin are crowded closely together, as may be understood from Figs. 6 and 7. Owing to the resilience of the bristles while thus held under the enormous pressure exerted by the pin, the bristles are held securely in position.

60 65 If for any reason one of the bristles in a particular tuft has a tendency to work loose, the other bristles around it, acting under pressure due to the presence of the pin, immediately expand or undergo a slight re-adjustment in position. Thus the pressure

as between the individual bristles of a tuft has a tendency to equalize itself, or become adjusted automatically. The net result is that the pressure is substantially uniform throughout all the bristles in a tuft, or for that matter throughout all the bristles in the brush.

Again, each bristle, by its connection with the cement mass in the hole with it, has a tendency to remain in the hole for the reason that the cement mass cannot move out past the pin. That is to say, independently of the adhesion of the cement mass to the wooden block, the cement mass as a unit is unable to pass the pin or even to stir from its initial position at the bottom of the hole, and of course a bristle adhering to or partially embedded within the cement mass cannot readily be extracted.

70 75 80 The use of cement as above described is desirable where the bristles are made of genuine or natural hair, such as horse hair, as bristles of this kind are smooth and glossy, and comparatively hard to hold in position.

85 90 95 If, however, the bristles are made of other materials and particularly of soft vegetable fibers such as tampico, the use of cement can be dispensed with, as indicated in Fig. 8. Here the pin 19 is driven through the tuft 19^b, and the bristles because of their rougher surfaces and coarser texture, as well as greater pliability are more easily formed under pressure. Hence they readily cling to the pin and to the block so as to hold without cement. Brushes made in this way are well adapted for scrubbing, and can be produced at low cost.

100 105 The block 8 is now finished and in its final form appears as indicated in Fig. 1, at 8^a.

I do not limit myself to the exact steps here recited, nor to the precise mechanism here shown, as variations may be made therefrom without departing from the spirit of my invention, the scope of which is commensurate with my claims.

110 I claim:

1. In a brush the combination of a block serving as a brush back and provided with holes, said block being further provided with a hole extending crosswise of said first mentioned holes and establishing communication therebetween, said second mentioned hole extending in a line located between the top and bottom of each of said first mentioned holes, tufts of bristles located in said first mentioned holes, each tuft being made up of separate bristles and having a length coinciding with the length of each bristle, and a rigid fastening member serving as a wedge fitting into said second mentioned hole, and extending transversely tightly through said tufts of bristles.

115 120 125 130 2. A brush comprising a body member provided with a number of holes, bristles ar-

ranged into separate tufts each occupying one of said holes, the bristles of each tuft being separate and each bristle having a maximum length coinciding with the length 5 of the tuft, each tuft being provided with an adhesive mass for preventing the removal of individual bristles from the tuft,

and a fastening member having generally the form of a pin and driven through a number of said tufts for the purpose of 10 causing them to fit tightly within the respective holes they occupy.

JOHN MORRISON, JR.
